Primary Examiner — Leanne Was-Englehart*Assistant Examiner* — Lacey Chey Bowman(74) *Attorney, Agent, or Firm* — Jose Cherson Weissbrot(57) **CLAIM**

The ornamental design for a baby car camera, as shown and described.

DESCRIPTION

FIG. 1 is a front perspective view of a baby car camera showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The broken lines in the figures are for the purposes of illustrating portions of the baby car camera, which form no part of the claimed design.
